US00D964978S

(12) **United States Design Patent** (10) **Patent No.:** **US D964,978 S**
(45) **Date of Patent:** **** Sep. 27, 2022**

(54) **CASE FOR MOBILE TELEPHONE**

(71) Applicant: **Guangzhou Yi SiMei Plastic Products Co., Ltd.**, Guangzhou (CN)

(72) Inventor: **Yiqiang Zhang**, Guangzhou (CN)

(73) Assignee: **Guangzhou Yi SiMei Plastic Products Co., Ltd.**, Guangzhou (CN)

(**) Term: **15 Years**

(21) Appl. No.: **29/814,024**

(22) Filed: **Nov. 2, 2021**

(51) LOC (13) Cl. **14-03**

(52) U.S. Cl.

USPC **D14/250**

(58) **Field of Classification Search**

USPC **D14/250**

CPC **A45C 11/00; H04B 1/3888; H04M 1/18**
